Darby & Darby

UNITED STATES PATENT OFFICE

PARIS R. FORMAN, OF RAHWAY, NEW JERSEY, ASSIGNOR TO NATIONAL PNEUMATIC COMPANY, OF NEW YORK, N. Y., A CORPORATION OF WEST VIRGINIA

AUTOMATIC RETURN TOGGLE SWITCH

Application filed February 2, 1929. Serial No. 337,105.

This invention relates to an automatic return toggle or over center switch.

One of the objects of this invention is the provision of a switch having an operating member and a switch arm arranged so that the switch arm is not operated until the operating member is moved past the center of its path of movement, and the provision of means for normally returning such switch 10 arm to one end of its path of movement.

A further object of this invention is the provision of a switch of this type in which the contact arm and contacts are so constructed as to provide wiping contact there- 15 between.

A still further object of this invention is the provision of a toggle switch having double contacts for the purpose of reducing arcing by reason of a simultaneous double break 20 in the circuit connected to the contacts and means for keeping the switch arm normally against one of said contacts.

A still further object of this invention is the construction of a toggle switch which is arranged to break one circuit and make another by means of a switch arm which operates very rapidly and means to normally have said switch arm tend to complete but one of 25 said circuits.

These and other objects, as will appear 30 from the following description are secured by means of this invention.

This invention resides substantially in the construction, combination, arrangement and 35 relative location of parts as will appear more fully from the following disclosure.

Referring to the drawing:—

Figure 1 is a front elevational view of my novel switch structure; and

Fig. 2 is a side elevational view thereof.

This invention provides a toggle or over center switch having one main bearing for simplicity with a secondary toggle bearing for throwing the switch arm after the operating member has moved over center, together with means for normally keeping said switch arm to one side of the over center position. In the arrangement disclosed the operating member must move past the center of 45 its path of movement before the switch arm 50

is snapped from one set of contacts to the other. This, like my copending application, Serial No. 222,782, filed September 29, 1927, concerns itself with the thought of quick acting over center toggle switches. In said application I have disclosed the general type of switch which I hereinafter disclose and use and to which I now add my novel adaptation which provides for normally returning said switch to one end of its stroke. The subject 55 matter of this disclosure is a structure which is to be used as an improvement upon and ancillary to the structure disclosed in my copending application hereinbefore referred to.

Referring to the drawing, I will describe 60 briefly the switch body as I have described it and its modifications at length in my copending application. The switch is shown providing a supporting member 1 of insulating material having holes therein for attaching 65 it to a support. Mounted in the member 1 is a shaft 3 upon which is journalled a hollow operating member 4 having a hollow projecting arm 5. A second insulating support 9 is mounted on the shaft or post 3 and the hollow structure is held in assembly by means of 70 nuts 6 which provide terminal connecting means for circuit wires. Contact means or posts 7 and 8 are also mounted between the supports 1 and 9. Pivotedly mounted on the 75 post 3 and within the operating member 4 is the switch arm 10 which has thereon notches 11 to increase the contact area of the arm with contacts 7, 8. Grooves are cut in each of the contacts as may be seen by observing 80 the structure as shown at numeral 11 in Fig. 2.

These notches are tapered so that wiping contact is made with the terminal contacts 7, 8 when the switch arm 10 is moved against or away from said terminal posts. A rod 12 85 is pivotally connected to the lever 10 and is mounted to slide through a washer 14 mounted within the operating member against the action of the spring 15.

This is the structure as I have delineated it 90 in my copending application and the operation of which I now explain as follows: When the operating member 4 is manually or mechanically swung by its projecting arm 5 between the supports about the post 3 it will 95 100

snap the switch arm 10 from the left to the right shortly after the rod 12, pivoted at 13, and off-centered from the axis of the post 3, moves past the center of its path of movement. The spring 15 which is compressed up to the time when the arm 10 begins to move provides the energy for swinging the switch arm from one set of contacts to the other, thus providing a switch of the two-way type. This switch as may be seen from the foregoing disclosure might ordinarily normally repose so that the contact arm 10 may contact with either the post 7 or 8, and this is substantially the disclosure and method of operation of the invention set forth in my copending application. However, I have found that for certain purposes this type of switch is best adapted to normally retain the switch arm 10 against one of these two contacts and intermittently cause it to contact with the other of said contacts. That is, I have found that for certain purposes it is preferable that the contact be normally made against one of the two posts 7 or 8 and especially and abnormally made by manually or mechanically forcing it against the other of said posts against the action of some resilient returning device, such as a spring, which will act to return said switch arm to its normal position the minute that it is released from the intermittent and abnormal force. It is my thought that it is preferable at times to have one circuit normally closed and another circuit normally open and by special intermittent throwing of my single-pole double-throw switch to open said normally closed circuit and to close a normally open circuit. I attain these new purposes by utilizing the type of switch I have hereinbefore described and adapting to its structure a resilient returning member so that the operating body 4 is normally held to one end of its stroke and will never pass the center point of its path of movement unless pushed across said point by a special actuating force. Referring to the drawing it will be seen that 16 represents an actual spring having end 17 firmly adjusted in the supporting body 1 of the switch structure and having its opposite end 18, after said spring is tensioned by properly winding it, located in the movable operating member 4. It is apparent that the effect of this spring is to normally hold the element 4 to one side of center and to correspondingly hold the element 10 to one side of center. However, when the arm 5 is grasped and forcibly moved against the force of the spring past center the contact arm 10 will quickly act, as I have disclosed it in my copending application, to make contact with the other contact post. When the arm 5 is released the spring will act to return the arm 5 to its normal sitting position and the contact arm 10 will quickly act to break the circuit against the intermittent post and make it against the normal post.

Although I have thus described my improvement as consisting in the spring embodiment adapted to be used with the novel structure set forth in my copending application it is quite apparent to one skilled in the art that any resilient returning member, other than a spring, might be properly adapted to be used for this purpose and I do not desire to be limited to the use of a spring in my structure, but merely to the thought of normally retaining a contact arm of the quick moving toggle type over-center switch against one end of its stroke.

In the drawing I have also shown the type of spring I use as being of helical form and it is apparent that this, too, is but one form of embodiment of my invention. I have shown, also, tentative locations for the ends of the spring at certain positions such as 17 and 18 and, although, at the present time, such locations seem to give practical and desirable results I do not desire to limit myself in this direction, but place the limits and scope of this invention as it is defined in the hereinafter appended claims.

From the foregoing disclosure it will be apparent that I have devised a new and novel form of toggle switch which is relatively simple in construction and which in the normal operation thereof provides means for reducing arcing by means of the wiping contact as well as a cleaning operation together with the provision of means for normally retaining such switch against one of two optional contacts.

It is also to be understood that the language contained in the following claims is intended to cover all the generic and specific features of the invention herein described, and all statements of the scope of the invention which, philologically speaking and as a matter of language, might be said to fall therebetween.

What I seek to secure by Letters Patent is:

1. In a single-pole double-throw switch, a support having a pivot pin and a plurality of contacts therein, said pivot pin forming one terminal of the switch, an operating member journaled on said pivot pin, a switch arm pivoted on said pivot pin, and means connecting said member and arm for snapping said arm from one contact to the other when said member is moved past the center of its path of movement together with means for normally holding said switch arm against one of said contacts.

2. In a single-pole double-throw switch, a support having a pivot pin and a plurality of contacts therein, said pivot pin forming one terminal of the switch, an operating member journaled on said pivot pin, a switch arm pivoted on said pivot pin, means connecting said member and arm for snapping said arm from one contact to the other when said member is moved past the center of its

path of movement, and a spring for normally holding said arm against one of said contacts.

3. In a single-pole double-throw switch, a support having a pivot pin and a plurality of contacts therein, said pivot pin forming one terminal of the switch, an operating member journaled on said pivot pin, a switch arm pivoted on said pivot pin and means connecting said member and arm for snapping said arm from one contact to the other when said member is moved past the center of its path of movement, said arm and contact being constructed to provide a wiping contact with each other, and resilient means to normally hold said operating member to one side of the center of said path of movement and thereby normally hold said switch arm against one of said contacts.

20 4. In a toggle switch, a pair of supports, a pivot post rigidly supporting said supports in spaced relation, contacts on said supports, a hollow member having a stop plate thereon movably supported on said post, a switch arm pivoted on said post within said hollow member and means comprising a rod having a stop plate thereon pivotally connected to said switch arm and extending through said stop plate in the hollow member and a spring 25 encircling said rod lying between the stop plates for causing said arm to swing from one set of contacts to another when said member is moved past the center of its path of movement, and resilient means for normally 30 causing said arm to remain against one of said set of contacts.

5. In a toggle switch, a pair of supports, a pivot post rigidly supporting said supports in spaced relation, contacts on said supports, 40 a hollow member movably supported on said post, a switch arm pivoted on said post within said hollow member, a rod slidably mounted in said hollow member and pivotally connected to said arm, and a spring encircling 45 said rod abutting against said member to cause said arm to snap from one set of contacts to another when said member is rotated about said post, and means to normally prevent such rotation thereby normally completing 50 ing continuously one circuit.

6. In a toggle switch construction, the combination of two spaced supports, a pivot post for holding the spaced supports in fixed relation, a plurality of contact posts secured between said spaced supports, said post comprising a reduced portion on which is slidably mounted contact members under spring pressure, a switch arm pivotally attached to said pivot post, a hollow member forming the 55 switch handle also pivotally mounted on said pivot post, a rod pivotally attached to said switch arm and extending into said hollow member and a compression spring encircling said rod whereby the switch arm is snapped 60 into said wiping contact with said contact 65

post when the hollow member is rotated, and spring means to normally prevent the rotation of said hollow member and keep the switch arm normally in wiping contact with one of said contact posts.

7. In a single-pole double-throw type of toggle switch, two contacts, a pivot post, a hollow member rotatably supported on said post, a switch arm pivoted on said post, resilient means for normally keeping said switch arm against one of said contacts and resilient means disposed in said hollow member to cause said switch arm to snap from one set of contacts to another when said hollow member is rotated about said post.

In testimony whereof I have hereunto set my hand on this 28th day of January A. D., 1929.

PARIS R. FORMAN.
